ORNAMENTAL DISPLAY DEVICE

Vincent B. Ream, West Hollywood, Fla.

Application October 22, 1957, Serial No. 691,635

2 Claims. (Cl. 240—10.1)

This invention relates to ornamental display devices wherein a multiplicity of variegated colored illuminated spot lights are projected in a radial manner to impinge upon wall areas and other adjacent objects.

The device comprises a hollow transparent shell wherein is disposed a source of illumination and color segments and with a concentric perforated cylinder being rotatable around the source of illumination and the color segments and whereby variegated colors are projected outwardly through the transparent shell with sufficient intensity as to be projected upon the surrounding walls or objects in a manner to create an ornamental decorative effect.

The invention further contemplates an enclosing shell of cylindrical form having a removable end portion that is provided with an electrical socket for the reception of the source of illumination and with the shell being also provided with a pronged plug for connection with a conventional receptacle for conducting electricity to the socket.

The invention further contemplates a shell of cylindrical form that is open throughout and with the shell at one end being closed by a detachable transparent end portion and at its opposite end having a conventional motor for actuating the perforated drum and with means carried by both the shell and the removable end portion whereby to automatically connect the source of electricity with the source of illumination when the end portion is engaged with the shell.

Novel features of construction and operation of the device will be more clearly apparent during the course of the following description, reference being had to the accompanying drawings, wherein has been illustrated the preferred forms of the device and wherein like characters of reference are employed to denote like parts throughout the several figures.

In the drawings:

Figure 1 is a side elevation of a device constructed in accordance with the invention,

Figure 2 is an end view thereof,

Figure 3 is an enlarged longitudinal section taken substantially on line 3—3 of Figure 2,

Figure 4 is a transverse section taken substantially on line 4—4 of Figure 3,

Figure 5 is a plan view of a modified form of a color segment sleeve,

Figure 6 is a fragmentary inner plan view illustrating the electrical connection for a removable cap and an associated lamp socket and the electrical connection from a pronged plug to a prime mover,

Figure 7 is a view similar to Figure 3, but illustrating a modified form of the invention and,

Figure 8 is a view illustrating a further use of the device.

Referring specifically to the drawings and particularly to Figures 1, 2, 3, 4 and 6, the numeral 5 designates a preferably clear plastic cylindrical shell that is open at its opposite ends. The shell at one end is closed by a cylindrical electrical motor 6, fixed within the open end of

2

the shell by screws or like fastening devices 7. The shell at its opposite end is closed by a semi-spherical cover 8, likewise preferably formed of transparent plastic. The cover 8 is connected with the shell 5 by an overlying flange 9, having frictional engagement with the shell and locked against accidental displacement in any desirable manner. Axially of the cover 8, there is provided a preferably integral stepped cylindrical collar 10, preferably having molded therein a metallic socket element 11, that constitute the socket and a source of illumination 12, such as a conventional incandescent lamp. The socket 11 is connected by conductors 13 to a pair of prongs 14. The prongs 14 are adapted to have engagement within a pair of spaced apart sockets 15 that are molded or otherwise formed upon the shell 5 at its forward open end. The sockets 15 have extended portions 16 that are connected by conductors 17 with terminals 18 carried by a connector 19, having prongs 20. The connector 19 and its associated elements are fixed to the shell 5 by a screw 21, although it should be understood that the connector 9 may likewise be molded integral with the shell. Also connected with the terminals 18 are a pair of conductors 22, that have electrical connection with the motor 6 and whereby, when the prongs 14 are seated with respect to the sockets 15 and the connector 19 as its prongs 20 engage within a conventional receptacle, the lamp 12 is caused to glow and the motor 6 actuated. The motor 6 is a low speed motor of well known construction.

Detachably and frictionally supported upon a reduced portion 23 of the collar 10 is a sleeve 24, open at its opposite ends. The sleeve 24 for its major length is provided with a plurality of longitudinally extending color segments 25 and with the segments being entirely around the sleeve. The sleeve 24 is concentric to and in spaced relation to the lamp 12 and with the lamp 12 being of a length to extend for the major length of the sleeve.

Fixed upon the shaft 6' of the motor 6, is a drum 26, having one end closed and provided with a connecting collar 27 that is fixed to the shaft 6' by a set screw 28. The drum is open at its opposite end and with the drum being rotatable under the influence of the motor 6 in concentric and spaced apart relation to the sleeve 24. The drum 26 is circumferentially perforated at 29 whereby light projected through segments 25 will pass through the apertures 29 and through the shell 5 and its spherical end 8 to be projected upon a wall or other area, creating an ornamental visual display. The apertures 29 may be of any particular configuration and may represent various objects, such as stars, moons, animals or birds and it will be apparent, that when the projected beams of light through the apertures strike a wall area, they will be relatively enlarged. Further, with the segments 25 being of various colors, there will be a continuous changing in the projected spots or other configurations in a gradual sequence from one color to the other as the apertures pass from one color segment to the other.

In the form of the invention illustrated in Figure 5, the sleeve 24' has its segments 25' arranged in a spiral form and whereby to further gradually shift from one color to another through the apertures of the drum 26. The segments 25 and 25' may either be formed upon the sleeves as painted strips or, the segments may be embodied as an integral or assembled relation to the sleeve.

In the form of the invention illustrated in Figure 7, the sleeve 24 has been omitted and the color segments 65 are painted or otherwise disposed upon the outer surface of the lamp 12' and whereby the illumination from the lamp 12' will pass through the several spirally disposed color strips 25a. In all other respects, the device is similar to that previously described with respect to the first form of the invention.

In Figure 8 there has been illustrated a further use

of the device wherein the drum 26, the sleeve 24 and the source of illumination 12 is embodied within a conventional clock radio and with the drum 26 being driven from the arbor of the clock and with the projected light passing through a lens 30, disposed within the top of the radio casing.

Operation

In the use of the device, with the parts assembled as illustrated, the prongs 20 are engaged within any convenient receptacle, causing the lamp 12 to glow and the motor 6 to rotate. Light will be projected through the segments 25, the apertures 29 and the body of the shell 5 to be projected upon surrounding objects or wall areas, imparting the very ornamental and soothing effect to persons in the vicinity. The device is particularly helpful to persons who suffer from insomnia and the soothing effect is beneficial in creating drowsiness. When a lamp is to be replaced, the cover 8 is shifted outwardly with the sleeve 24, the sleeve 24 is then removed from the reduced portion 23 of the collar 10 and the lamp replaced. After the lamp has been replaced the sleeve is again engaged and the cover 8 together with the prongs 14 shifted to a closed position to establish the electrical connection to the socket of the lamp. The replacement of the lamp 12' is accomplished in a similar manner, with the exception of the necessity of removing the sleeve 24.

It will be apparent from the foregoing that a very novel and decorative device has been provided and whereby to create a very desirable variable and multiplicity of light projections upon surrounding objects. The device is cheap to manufacture, is strong, durable and applicable in various positions. It may be found necessary or desirable that the connector 19 be disposed upon the end of the device as illustrated in Figure 1, thus further enlarging the usefulness or positioning of the device.

It is also contemplated that the color sleeve 24 shall be rotatable around the source of light of the perforated drum 26 but held stationary in which case, the sleeve 24 will be mounted upon the shaft 6' similar to the connection illustrated with respect to the drum 26 and, in such case the drum 26 will be carried by the collar 10, with the collar 10 being dimensioned to support the drum. The function will be substantially identical, and with the only difference being that the color sleeve 24 rotates while the drum 26 is stationary, but with the parts being in their same relative position with respect to the source of illumination 12.

It is to be understood that the invention is not limited to the precise construction shown, but that changes are contemplated as readily fall within the spirit of the invention as shall be determined by the scope of the subjoined claims.

Having described my invention, what I claim as new and desire to secure by Letters Patent is:

1. An illuminated display device of the character described that comprises a cylindrical transparent housing that is open at its opposite ends, a cylindrical electric motor that has interfitting engagement within one open end of the housing and with the motor having a drive shaft that is axial with respect to the housing, a semi-spherical transparent closure cap for the opposite end of the housing, the closure cap being detachably connected with the housing, the closure cap having an enlarged centrally arranged portion that is provided with an electric socket, an incandescent lamp engageable within the socket to be axially disposed with respect to the housing, the enlarged portion of the cap being externally cylindrical, a fixed drum supported upon the cylindrical portion and with the drum being provided with a circumferentially arranged group of color strips, the drum being concentric to and in spaced apart relation to the lamp, a second drum that is arranged outwardly of and in spaced apart concentric relation to the first named drum and with the second named drum being rotatably connected to the shaft of the motor, a plug-in connector carried by the housing for connection with a source of electrical energy, separable connector elements carried by the housing and the cap and with the elements of the housing being connected to the plug, and with the elements of the cap being connected with the socket, the said motor being also connected with the plug and whereby by the motor and the lamp are simultaneously energized, the said second named drum being circumferentially closely perforated and whereby various colors passing through the segments will be projected through the apertures and through the transparent housing and the cap to impinge upon surrounding objects.

2. The structure according to claim 1 wherein the connector elements of the housing comprise a pair of sockets that are molded into a lug formed upon the housing at its lower side, the said connector elements of the cap comprising a pair of prongs that are molded into a lug formed upon the cap to be axially engaged within the sockets when the cap is engaged with the housing as a closure, the said plug having a pair of terminals that are disposed inwardly of the housing and with a pair of prongs that project outwardly of the plug, a pair of conductor wires connected with the terminals and with the sockets, a pair of conductor wires connected with the first named prongs and with a lamp socket and a pair of wires connected with the terminals and with the electric motor.
